KNUT ANDREAS KNUTSEN, OF LJAN, NORWAY

MACHINE FOR SORTING PERFORATED CARDS

Application filed November 21, 1929, Serial No. 408,887, and in Norway September 28, 1929.

This invention relates to a machine for sorting perforated cards.

These cards are ordinarily perforated or otherwise marked to effect a record, frequently of a numerical value. For this purpose each card may be considered as divided in columns, each column including a number of divisions or points with different numerical values. By punching through or otherwise marking the card at one of these points, the column in question will be given a certain value. It is the purpose of the sorting machine to examine the same column on each card of a pile of cards and sort or arrange the cards in certain groups, for instance in such a manner that each group consists only of cards which have been punched or otherwise marked at the same point in the selected column.

20 The examination of the column may be effected by passing the card across a feeler. If a point or figure in the column being examined has been punched through, the feeler will close an electric circuit. Such electric sorting machines are previously known.

It is the object of this invention, while retaining an electric circuit closed by the feeler and a single magnet energized by this circuit to render the machine completely automatic in operation, thus avoiding disadvantages and defects of previously known machines.

Another object is the provision of suitable devices to facilitate the operation and supervision of the machine by an attendant.

35 The invention is described herein with reference to the drawings, which show one example of an embodiment of a machine according to the invention. Fig. 1 is a vertical section through the longitudinal axis of the machine, Fig. 2 a vertical cross-section on the line A—A in Fig. 1, Fig. 3 is a side view, Fig. 4 is a plan view of part of the machine and Figs. 5 and 6 are details.

45 From a magazine 1 where the cards are piled they are in known manner carried horizontally one by one, by means of a feeding device 2, between rollers 3 beyond a feeler 4 and further between rollers 5 and 6.

50 On leaving the rollers 6, the card is caught by one of the conveying beams 7, which are

fastened to an endless chain 8, and is conveyed, sliding on the slideway 9, past a series of flaps 10, which in opened position let the card fall down into the receiving compartment or pocket 11 belonging to said flap. 55

If one of the figures in the column on the card being examined by the feeler 4, is punched through, an electric circuit will be closed at the moment when the perforation passes the feeler. According to the invention, the closing of this circuit energizes a magnet 24 which serves to actuate an operating device 20 provided with a series of cams 22, which device in turn brings one of a series of catches 12 carried on the conveying beams 7, in working position. In this working position the catch operates at the right moment to automatically open the flap 10 of that compartment 11 for which the card is destined, so that the card will slide down in 70 this compartment. These catches 12 are arranged on each conveying beam in a line, which may be disposed at any angle with respect to the direction of motion of the card, in the present example perpendicular to the 75 same. There is one catch for each movable flap, in this case eleven catches are provided on each conveying beam. The catches 12 may, of course, be placed on a separate beam independent of the conveyor for the cards. 80

The catches are movable and have two fixed positions, one zero or initial position, as indicated by 36, and one working position 37 (Fig. 5). The zero position is the normal position, to which the catch is always carried 85 back automatically by each revolution of the beam. In working position, the catch will strike a certain one of the pivoted arms 13 and thus open a selected flap. On every beam, catch No. 1 when in its working position will strike arm 13 belonging to flap No. 1, catch No. 2 will strike the arm belonging to flap No. 2 and so on. When the catches 12 are in the reset or zero position, they will not strike any of the arms 13. The arm 13, 95 when struck by the catch 12, turns shaft 14, whereby arm 15 is moved, Fig. 6. This arm in turn moves the double arm 16, against which the arm 17, fixed to the flap, rests. When arm 16 is moved, a spring 18 opens the 100

flap. The opening takes place when the leading edge of the advancing card is a short distance from the flap. In the embodiment shown, arm 13 is actuated by a catch on the 5 second beam ahead of the beam that pushes the card.

When the flap opens, the card is pushed down in the compartment by the beam, and the flap is again shut by the cam wheel 19, 10 carrying the cam 46, there being one cam for each pocket, which cam positively shuts the flap just at the moment when the conveying beam has passed the flap, the cam 46 at that moment striking arm 17. The cam 15 wheels 19 are arranged on a longitudinal shaft 45, which makes one rotation for every beam passing the flap.

As already mentioned the catch 12 is brought into working position by the operating 20 device 20. This operating device comprises a supporting member 21 to which is attached a number of cams 22, one cam for each movable flap. In this case there are eleven cams. The cams are thin plates, so mounted 25 that their planes are parallel to the direction of motion of the card. The distance between adjacent cams in the direction perpendicular to the motion of the card, is exactly the same and equal to the distance between the 30 catches 12, also measured perpendicular to the direction of motion of the card. The cams are mounted on a line, which may be perpendicular to the moving direction of the card, or as in this case on a line inclined to 35 this direction, in such a manner, that the distance between each two adjacent cams, measured in the direction of motion of the card, is the same and equal to the distance which the conveying beam travels while the card, 40 being examined by the feeler, moves a distance equal to the distance between two immediately successive points or figures in the same column on the card. The motion of the conveying beam is controlled in relation 45 to the motion of the card when passing the feeler, in such way that when a card is in a certain position relative to the feeler a conveying beam always is in a certain position relative to the operating device 20 or to any 50 part of the card guideway. It is not necessary that the velocity of the conveying beam be equal to the velocity of the card at the feeler. In the present case the velocity of the beam is greater.

55 The operating device 20 is placed immediately above the rails on which the conveying beams slide. In the zero or reset position the catches 12 will be carried between the cams 22 without touching the same. On 60 account of the inclination of the row of cams in relation to the direction of motion of the card, there will at any moment be only one catch 12 alongside of a cam 22 or between two cams.

65 When a card reaches the feeler 4, the oper-

ating device 20 will always be in reset or zero position. It is kept in this position by spring 38 which presses the operating device 20 against the inner end of the armature 23 belonging to magnet 24. When a hole 70 punched in the card passes the feeler, an electric circuit will energize the magnet 24. The armature 23 will be attracted and spring 38 will move the operating device 20 toward the left (Fig. 2), which will be held in the new 75 position by the stop and push arm 25, which in turn is kept in position by the fixed stop 26 and spring 27. The operating device 20 is permanently retained in the horizontal plane by means of two springs 28, which press the 80 operating device against balls 29, rolling on the horizontal frame 30. In initial position as well as in shifted position, the operating device 20 will have such position that the catches 12 on the conveying beams will not 85 strike the cams 22, but will move between or alongside of the same. When all numbers in the column of that card which is being examined have passed the feeler, the cam 31 will move the push arm 25 and thus push the 90 operating device 20 back, so that the device is held in its initial position by the end of the armature 23 at the moment when a new card reaches the feeler. The cams 22 are each pivotally mounted on a pivot 47 on the 95 operating device 20 and are held in position by a spring 48, in such manner that the cam if accidentally struck on its front by a catch 12 may give way and let the catch pass.

The direction of motion of the operating 100 device 20 is perpendicular to the direction of motion of the card and the conveying beams. If a conveying beam is just below the operating device 20, so that one of the catches is just alongside one of the cams, and the above 105 mentioned electric circuit is closed at this moment, then the operating device 20 will move sideways and the cam 22 will push the catch 12 into working position. As there is at a given moment only one catch alongside a cam, only one catch will be brought in 110 working position, and the particular catch moved depends on the position of the conveying beams relative to the operating device 20. Catch No. 1 will always be moved 115 by cam No. 1, catch No. 2 by cam No. 2 and so on. When a catch 12 on the conveying beam is brought into working position, it remains in this position until the flap that belongs to that catch is opened. The catch 120 then is automatically carried back into the initial position, which position the catches always have when they again are carried underneath the operating device 20.

The conveying beams travel on the slide 125 41, which keeps the beams in their correct position. The beams have on their lower end a projecting edge 42, which edge supports the card when the beam pushes the card forward on the card guide. On their upper 130

sides the cards are held in horizontal position by means of two horizontal rails 35 and two stretched strings 44.

Having now described the different elements of the machine, we shall follow the operations that take place when a card passes through the machine. The columns of the card usually contain the numbers from 9 to 0. We punch through for instance the number 9 in a certain column, adjust the feeler to examine this column and put the card into the magazine. When the machine moves, the card is carried underneath the feeler. At the moment when the number 9 on the card is just underneath the feeler, a conveying beam is just underneath the operating device 20, in such manner that catch No. 1 on the beam is just on the side of the first cam. When the perforated portion of the card passes the feeler, a circuit will be closed, the armature of the magnet attracted, the spring 38 moves the operating device 20 sideways and catch No. 1 is brought into working position.

When the machine is moved further, the card is carried along, and just before it reaches the first flap, the catch No. 1 will open the flap, and the card slips down into the first pocket, which in this manner will receive all cards punched through, but no other cards.

If the card has no perforation at the point representing numeral 9', but is perforated to represent numeral 8, the electric circuit will not be closed until the point corresponding to numeral 8 passes underneath the feeler. At the same time the beam will have moved further on underneath the operating device 20, so that catch No. 2 on the beam will now be alongside cam No. 2 on the operating device 20. When the operating device 20 then moves sideways, cam No. 2 will push catch No. 2 on the beam into working position. None of the other catches will be moved, because catch No. 1 has now moved away from cam No. 1 and catch No. 3 has not yet reached cam No. 3. When the machine moves still further, the card is carried along till just before it reaches flap No. 2 and catch No. 2, which is in the working position will open this flap and the card will slide down in pocket No. 2, which in this way will receive all cards perforated to represent numeral 8, and no other cards. In the same way the operations take place when the card is perforated at other points to represent other numbers.

The frame of the machine consists of a stationary lower part 40 and a pivoted part 39. The pivoted part which consists of two long and stiff beams 32, held in fixed relation to each other by the transverse pieces 33, is mounted on the shaft or axle 34. On the pivoted part are arranged all slides and guide rails for the conveying beams. The

double endless chain runs over two pairs of chain wheels one pair of which rotates on the same shaft on which the pivoted part of the frame may be mounted. The second pair of chain wheels is mounted resiliently in the other end of the pivoted frame. Shaft 14 and arm 13 are also mounted on the pivoted frame, as well as the two guide rails 35. When turning the upper frame about shaft 34, all the parts mentioned will thus be lifted from the card guide 9, and leave this quite free, with the exception of the two stretched strings 44, which are fixed to the stationary frame.

Having thus described the invention what is claimed as new and desired to be secured by Letters Patent is:

1. A machine for sorting perforated cards of the type described which comprises in combination, a series of compartments, a slideway above said compartments, conveying means for moving the cards along said slideway, a plurality of flaps, one for each compartment, in said slideway for causing the cards to fall into the compartments to which they are intended, pivoted arms for operating said flaps, a plurality of series of pivoted catches carried by said conveying means, and disposed at right angles to the direction of travel of the conveying means, each catch of a series being adapted to be swung into an operative position for actuating one of said pivoted arms, a single series of cams disposed along a line forming an acute angle with the direction of travel of the conveying means, a common supporting member for all said cams adapted to slide in a direction at right angles to the direction of travel of the conveying means, an electro-magnet for operating said cam supporting member and a feeler adapted to close the circuit of said electromagnet according to the position of the hole provided in each card, whereby one of the cams is caused to swing one of the catches of one series into its operative position.

2. A machine for sorting perforated cards of the type described comprising in combination, a series of compartments, a slideway above said compartments, conveying means for moving the cards along said slideway, a plurality of flaps, one for each compartment, in said slideway for causing the cards to fall into the compartment for which they are intended, pivoted arms for operating said flaps, a plurality of series of movable catches carried by said conveying means, each catch of a series being adapted to be brought into an operative position for actuating one of said pivoted arms, a single series of cams for bringing only one catch of a series at a time into said operative position, an electromagnet for operating said series of cams, a feeler adapted to close the circuit of said electromagnet according to the position of

the hole provided in each card, and a frame adapted to support said conveying means, said frame being pivotally mounted on the machine.

5. A machine for sorting perforated cards of the type described comprising in combination, a series of compartments, a slide-way along said compartments, conveying means for moving the cards along said slide-way, two axes for supporting said means, a plurality of flaps, one for each compartment, in said slide-way for causing the cards to fall into the compartments for which they are intended, pivoted arms for operating said flaps, a plurality of series of movable catches carried by said conveying means, each catch of a series being adapted to be brought into an operative position for operating one of said pivoted arms, a single series of cams for bringing only one catch of a series at a time into said operative position, an electromagnet for operating said series of cams, a feeler adapted to close the circuit of said electromagnet according to the position of the hole provided in each card, and a frame adapted to support said conveying means, pivotally mounted about one of the axes of said conveying means.

4. A machine for sorting perforated cards of the type described which comprises in combination, a series of compartments, a slide-way above said compartments, conveying means for moving the cards along said slide-way, a plurality of flaps, each corresponding to a compartment, in said slide-way for causing cards to fall into the compartments to which they are intended, a plurality of pivoted arms for operating said flaps, a plurality of series of movable catches carried by said conveying means, each catch of a series being adapted to be brought into an operative position for actuating one of said arms, sliding means, adapted to move transversely of said conveying means, for bringing only one catch of a series at a time into said operative position, electric means for directly operating said sliding means, and a feeler for controlling said electric means in accordance with the position of the hole punched in each card.

5. A machine for sorting perforated cards of the type described which comprises in combination, a series of compartments, a slide-way above said compartments, conveying means for moving the cards along said slide-way, a plurality of flaps, each corresponding to a compartment, in said slide-way for causing cards to fall into the compartments to which they are intended, a plurality of pivoted arms for operating said flaps, a plurality of series of movable catches carried by said conveying means, each catch of a series being adapted to be brought into an operative position for operating one of said arms, sliding means, adapted to move trans-

versely of said conveying means, for bringing only one catch of a series at a time into said operative position, an electro-magnet for directly controlling the displacement of said sliding means, and a feeler adapted to close the circuit of said electro-magnet according to the position of the hole provided in each card.

6. A machine for sorting perforated cards of the type described which comprises in combination, a series of compartments, a slide-way above said compartments, conveying means for moving the cards along said slide-way, a plurality of flaps, one for each compartment, in said slide-way for causing the cards to fall into the compartments to which they are intended, pivoted arms for operating said flaps, a plurality of series of pivoted catches carried by said conveying means, and disposed along a line which intersects the direction of travel of the conveying means, each catch of a series being adapted to be swung into an operative position for actuating one of said pivoted arms, a single series of cams disposed along a line which intersects the direction of travel of said conveying means, an electro-magnet for directly controlling the displacement of said cam supporting member, and a feeler adapted to close the circuit of said electro-magnet according to the position of the hole provided in each card, whereby one of the cams is caused to swing one of the catches of one series into its operative position.

7. A machine for sorting perforated cards of the type described which comprises in combination, a series of compartments, a slide-way above said compartments, an endless chain conveyor for moving the cards along said slide-way, a plurality of pivoted flaps, one for each compartment, in said slide-way for causing the cards to fall into the compartments for which they are intended, a plurality of pivoted arms for operating said flaps, a plurality of series of pivoted catches carried by said conveyor and disposed along a line which intersects the direction of travel of said conveyor, each catch of a series being adapted to be swung into an operative position for actuating one of said pivoted arms, a single series of cams disposed along a line which intersects the direction of travel of said conveyor, a common supporting member for all of said cams adapted to slide in a direction at right angles to the direction of travel of said conveyor, an electro-magnet, a pivoted armature for said electro-magnet, a spring for urging said supporting member against said armature when the latter is in its position of rest, whereby said supporting member is displaced by said spring when said armature is attracted by said electro-magnet, and a feeler adapted to close the circuit of

5 said electro-magnet according to the position of the hole provided in each card, whereby one of the cams is caused to swing one of the catches of one series into its operative position.

8. In a machine for sorting perforated cards of the type described, the combination with a conveyor for the cards, of a series 10 of card receiving stations disposed at intervals along the path of movement of the conveyor, a plurality of discharging devices, one located at each station and cooperating with said conveyor for effecting discharge of a selected card from the conveyor, a series of 15 movable catches carried by said conveyor, each catch being allocated to one only of said devices for initiating operation of the latter, said catches being arranged in rows extending transversely of the conveyor and 20 being individually movable from inoperative to operative positions, a plurality of catch engaging members arranged in a row extending transversely of the conveyor and angularly disposed with respect to the rows 25 of catches, said members normally occupying positions intermediate the individual paths of movement of said catches, and means acting in response to the presence of a perforation in a card for shifting said members as a unit laterally of the conveyor, whereby the particular catch engaged and 30 rendered operative by the associated member

is determined by the relative position, lengthwise of the conveyor, of the members and catches.

9. In a machine for sorting perforated cards of the type described, the combination 70 with a conveyor for the cards, of a series of card receiving stations disposed at intervals along the path of movement of the conveyor, of means for effecting discharge of cards carried by the conveyor at stations selected in 75 accordance with the arrangement of the perforations on the cards, said means including a plurality of rows of catches extending transversely of the conveyor and carried thereby, each catch in each row being allocated to one only of said stations to initiate discharge of a card at such station, a plurality of catch engaging members arranged transversely of the conveyor and shiftable 80 laterally thereof as a unit, said catch engaging members being positioned intermediate the individual paths of movement of said catches and being arranged in a row extending at an angle to the rows of catches, and means for shifting said catch engaging members laterally, whereby the relative position, 85 lengthwise of the conveyor, of the catch engaging members and the catches at a given instant determines the particular catch engaged by the associated member, and means 90 for rendering operative a catch so engaged. 95
